UNITED STATES PATENT OFFICE.

MARSHALL B. LLOYD, OF MENOMINEE, MICHIGAN, ASSIGNOR TO THE LLOYD MANUFACTURING COMPANY, OF MENOMINEE, MICHIGAN, A CORPORATION OF MICHIGAN.

PERAMBULATOR.

1,319,479.

Specification of Letters Patent.

Patented Oct. 21, 1919.

Application filed September 18, 1916. Serial No. 120,768.

To all whom it may concern:

Be it known that I, MARSHALL B. LLOYD, a citizen of the United States, and resident of Menominee, Menominee county, Michigan, have invented certain new and useful Improvements in Perambulators, of which the following is a specification.

My invention relates generally to perambulators and relates more particularly to 10 the body and hood portions thereof.

The general object of my invention is to provide a hood and an associated body which shall be more conveniently adapted to the use intended than those hitherto provided.

Further objects of my invention are to provide a hood which shall be of improved appearance; which shall facilitate the removal of the child from the perambulator; 20 which shall provide better and safer protection against the weather; and which shall be of such construction that a shield or covering can be quickly and easily applied when it is desired to inclose the perambulator body.

My invention consists generally in the form, arrangement, and combination of parts, whereby the above named objects, together with others which will appear herein- 30 after, are attained; and my invention will be more readily understood by reference to the accompanying drawings illustrating the preferred construction thereof, and wherein;

Figure 1—is a perspective view of a perambulator body and hood embodying my invention.

Fig. 2—is a side elevation of the body and hood with the hood separated and a shield or covering mounted between the 40 hood parts.

Fig. 3—is a plan view of the perambulator in the condition shown in Fig. 2.

Fig. 4—is a perspective view of a covering or shield detached from the hood.

Fig. 5—is a detail view illustrating the construction and coöperation of the hood frames and of the intermediate support for the shield member.

Fig. 6—is a detailed fragmentary plan view illustrating the construction of the hood pivots; and

Fig. 7—is a sectional detail view illustrating means for locking the hood parts together.

It is the common practice in the peram-

bulator art to mount a hood, pivotally upon the body, so that the hood may be swung to various positions for the purpose of protecting the child, as for example, from too intense a light, a strong wind, or from rain. 60 These hoods have hitherto consisted of a one-piece structure, covered with cloth, ratan, reed or other suitable material. It has also been the common practice to provide a covering, which is stretched between 65 the front edges of the hood and the front of the carriage, when it is desirable entirely to inclose the child; such for example, as in stormy weather or to protect from mosquitos and flies. The hoods hitherto provided have been of such construction as to greatly increase the bulk of the carriage because when they are made of a size to give sufficient protection, they project considerably above the body of the carriage, even in 70 their lowermost position. As a result of this fact, a larger place is required in which to store the carriage, and furthermore, in shipping the carriage a crate considerably larger than the size of the body and gear 75 must be provided in order to inclose the hood. Again, the hood being large, and relatively heavy, greatly unbalances the carriage when it is moved to one side of the center. The hitherto customary hood is also 80 objectionable in that in its lowest position, it projects considerably above the top of the carriage body, with the result that it is difficult for the attendant to place the child in the carriage and to remove it therefrom. 85 In addition to the mechanical and utilitarian disadvantages of prior hood structures, having the customary one-piece relatively large hood, is the disadvantage of a non-symmetrical structure which destroys 90 the pleasing lines of the perambulator, and in short, detracts from its beauty.

I have devised a novel structure, whereby these objectionable features are overcome and a perambulator of beauty and strength 100 provided which, at the same time, is conveniently adapted to the uses intended. To this end, instead of making the hood in a single or unitary form, I make it in a plurality of parts which can be readily combined, when 105 desired, to give a hood area equal to the combined area of the component parts; and which can be easily and quickly separated to dispose the parts of the hood in a manner best adapted for the particular and vary- 110

ing conditions. I preferably mount the hood centrally on the perambulator so that the parts can be swung to either side, thereof, or so that part can be moved or swung 5 to one side of the center, and part to the other side. By so moving and placing the parts, the perambulator is given a symmetrical shape which greatly enhances its beauty; reduces the strains due to unbal- 10 ancing; reduces the bulk of the crate for shipping; and greatly facilitates the placement of the child in, and the removal of the child from the perambulator.

Having thus generally stated the objects 15 and purposes of my invention, and having alluded to the structure for accomplishing these objects and purposes, I shall now describe in detail, the preferred structure illustrated in the drawings.

20 In the drawings, 1, represents the body of a baby carriage which may be of any suitable form, construction or character. In practice, the body is mounted upon a framework, provided with wheels and which is termed the gear, but inasmuch as my invention is not concerned with the gear structure, I have not thought it necessary to illustrate same in detail. I have, however, shown the gear in Fig. 1 in dotted lines in order to 25 show its general location with respect to the body. Attached to the gear is a handle 2, for the purpose of conveniently propelling the carriage. As will be described more fully hereafter, the handle limits the downward movement of the hood, with the result that in prior hood structure of usual construction, a considerable portion projects 30 above the upper edge of the perambulator body.

40 Preferably centrally of the body, I provide brackets 4, on each side along the upper edge 3, and thereto, I secure the hood members. In this instance I have provided a hood composed of two parts, 5 and 6, each 45 of which is pivotally connected to the central pivots 7'. The construction of the hood frames and their attachment to the center pivots will be better understood by reference to Figs. 5 and 6. Each hood member in 50 this instance comprises two U shaped members 7 and 8, to the free ends of which metallic members 9, are secured, which in turn are provided with holes for the reception of the pivots 7'. The pivot 7', is attached to 55 the supporting brackets 4, by means of devices 10, through which the brackets 4, pass. In order that the hood members will remain in any desired placed position against any normal forces, such for example as their 60 weight, tending to move them, I provide the central pivots with a spring washer or friction disk 12, which can be suitably compressed to provide necessary frictional contact. The described construction enables the 65 parts 5 and 6, to be moved to the positions

indicated by the dotted lines in Fig. 1, or in other words, to a position in which they are substantially flush with the top of the perambulator body. They can be moved to this position without interfering with or 70 contacting the handle 2, because only part of the full hood extends below the top of the body. When the hood members are in this position, that is, substantially flush with the top of the body, the attendant can conveniently place the child in the carriage or remove it therefrom, there being no projecting portion of the hood to interfere with such action. Again, when the hood parts are moved to this position, the perambulator 80 can be stored in a smaller space, and can be placed in a smaller crate for shipping purposes. This last named item, is of considerable importance, particularly in relation to non-collapsible carriages, such for example, 85 as a reed carriage, which is assembled in the factory and shipped in assembled condition. Carriages of this type, because of their large bulk and relatively small weight, are expensive to ship and any construction which 90 reduces the bulk for shipping purposes is of great value, and particularly so if the utility is not impaired. In my structure, not only is the utility not impaired, but conversely, the utility is actually greatly enhanced. If desired, both portions of the hood can be secured together to remove as a unit. In this event, they appear substantially like the hitherto usual one-piece hood as is well shown in Fig. 1. In order to hold 95 the hood parts together, I prefer to provide a lock of such construction that it will hold the parts together against the forces necessary to swing the hood against the resistance of the friction disks, and which at the same 100 time, when subjected to an additional tension, will permit them automatically to separate, as for example, where the hood parts are pulled in opposite directions. I also prefer to make the securing means of such construction that when the hood parts are forcibly moved together, or into contact one with the other, they will automatically be locked in that relation. For this purpose, any suitable means may be provided, such for 105 example as catch 20, best shown in Fig. 7. This catch comprises a lever 21, mounted in a recess 22, in the frame of one of the hood members. This lever is mounted on a pivot 23, and is normally held in the inoperative position shown in Fig. 7, by means of a coiled spring 24, one end of which is mounted in the frame and the other end of which engages the lever. Upon the upper 110 end of the lever, I provide a latch member 25, preferably made of spring material, and in the adjacent frame of the opposite hood member I provide a plate 26, having an opening 27, so positioned relative to member 25, that the member will strike the edge 28, 115

be depressed thereby, and spring into position behind the plate when the hood frames are moved into intimate contact. I should here state that I prefer to make the lever 25, of such length that it will normally be entirely within the recess 22, so that it will not be unsightly and also to the end that there shall be no sharp edges to catch the clothing or to injure the child or attendant.

10 In order that the latch 25, will be properly thrown out to engage with the plate 26, I provide a protruding portion 30, which is preferably rounded, and which when the frame parts are moved together, engages the plate 26, and consequently throws the latch 25, outwardly. The protruding portion 30, of the latch being relatively small, and presenting a smooth surface, is not objectionable, either as marring the appearance of 20 the hood or of being physically dangerous.

As before stated, one of the advantages of my novel hood, is that the parts can be separated to form, with the body, a more balanced appearance, and also to the end 25 that, when desired, a shield or covering can be stretched between the parts, as is well shown in Fig. 2. This shield or canopy 30 can be made of various materials, such for example, as cheese-cloth, hospital-gauze, or corduroy for use under differing weather conditions. When the hood parts are rather widely separated, as indicated in Fig. 2, I prefer to provide a central support, which 35 suitably elevates the canopy and also enhances the appearance. In this instance, I have provided a U shaped bail 31, which approximates the shape of the frame members of the hood, and which has its free ends 32', mounted on the central pivots 7'. The bail 40 31, is preferably of such height that it can be swung or moved to occupy a position within either of the hoods, as illustrated in one position, within one of the hoods by means of dotted lines in Fig. 5. I prefer 45 also to provide the bail 31, and the hood frame members 7, with devices 32, to which the cloth, shield or canopy can be secured for convenient attachment and removal. A 50 convenient form of device for this purpose is the usual glove-button construction, one part being secured to the hood, and the complement being secured to the canopy. Where the canopy is made of light relatively loose material, such for example, as 55 cheese-cloth or hospital-gauze, there is considerable difficulty in properly attaching it to the hood frame. I have solved this difficulty in a novel way by securing strips of relatively heavy material, such for example, 60 as heavy cloth, along the canopy in a position suitable for co-action with the fastening devices of the hood, and in or through these strips, I provide complementary fastening means, such as the button-hole or one 65 portion of a glove-button fastener. In Fig.

4, I have depicted generally such a construction, and therein 35, is the canopy covering, and 36, are the strips of relatively heavy material, secured to the canopy in any suitable way, as for example, by sewing, and in the same figure 37, indicate the fastening devices for complementary engagement with the fastening devices 32, of the hood members and of the canopy bail.

If desired, the canopy can remain in place 75 when the hood parts are moved together to form a unit structure and on the other hand, if desired, the canopy can be readily removed. When the canopy is left in place, it is simply necessary to swing the hood 80 parts together because the canopy covering collapses or folds inwardly arranging itself compactly within the hood parts. Furthermore, when the canopy is left in position, it is not visible from the outer sides of the 85 hood, so that to all intents and purposes, the hood appears substantially as one of usual construction. When desiring to use the canopy to inclose body, it is but necessary to separate the hood parts and canopy 90 will automatically assume its proper position.

It is thought that this disclosure is sufficient to teach the construction and operation of means whereby the substantial objects of my invention may be obtained, but inasmuch as this disclosure will also suggest to others, skilled in this art, various modified constructions whereby these substantial objects and purposes can be attained, I do not wish to be limited to the specific construction, herein shown and described, except only as may be necessary by limitations in the hereunto appended claims.

I claim:—

1. A perambulator comprising in combination a body portion, a hood pivotally mounted thereon and of a size such that it can be swung as a whole from a position 110 over the rear part of the body to a position over the front part of the body, said hood comprising two separable parts formed so that, if desired, one part may be disposed over one part of the body and the other 115 part over the other part of the body.

2. A perambulator comprising, in combination, a body portion, a hood pivotally mounted centrally thereon and of a size such that it can be swung as a whole from 120 a position over the rear part of the body to a position over the front part of the body, said hood comprising two separable parts formed so that, if desired, one part may be disposed over one part of the body and the 125 other part over the other part of the body.

3. A perambulator comprising, in combination, a body portion, a hood pivotally mounted thereon and composed of a plurality of separable parts, each part forming 130

- a small transversely disposed hood, and the hood parts being of such size that they may be swung to a position surrounding the body.
5. 4. A perambulator comprising in combination a body portion, a hood pivotally mounted thereon and of a size such that it can be swung as a whole from a position over the rear part of the body to a position over the front part of the body, said hood comprising two separable parts formed so that, if desired, one part may be disposed over one part of the body, and the other

part over the other part of the body, and a latch carried by the hood part and engaging the other, when in associated position, and serving to prevent accidental separation.

In testimony thereof, I have hereunto set my hand, this 11th day of September, 1916, 20 in the presence of two subscribing witnesses.

MARSHALL B. LLOYD.
